UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL-FIXTURE-SUPPORTING DEVICE.

Application filed June 23, 1921, Serial No. 479,738. Renewed May 17, 1926.

My invention relates to electrical fixture supporting devices and connections therefor.

One of the objects of my invention is to provide an improved fixture supporting device, which fixture can be readily connected and disconnected with respect to the receptacle, both electrically and mechanically.

A further object of my invention is to provide such a device which will be simple 10 in construction, cheap to manufacture and durable and efficient in use.

Further objects will appear from the detailed description to follow and from the appended claims.

15 In the drawings in which an embodiment of my invention is shown—

Figure 1 is a vertical axial section showing a fixture, receptacle, and connector device;

20 Fig. 2 is a front view of the receptacle; and

Fig. 3 is a rear view of the connector device and fixture canopy.

The construction shown in the drawings 25 comprises a fixture 10, (the stem 11, and the canopy 12 alone being shown) an electrical receptacle 13, a plug-in device 14 for electrically connecting the fixture 10 with the receptacle 13, and a mechanical connecting 30 member or bracket member 15 for mechanically connecting the fixture with respect to the receptacle.

The plug-in device 14 is carried by the connecting bracket 15, being bodily slidably 35 mounted thereon, to permit the necessary lateral movement of the connecting bracket 15 for making the mechanical connection without interference with the insertion of the contact blades 16 into the openings 17 provided in the receptacle.

40 The mechanical connecting member 16 is secured to the supporting plate 18 (which may be a sort of cover for the outlet box) by means of four hook members 19, which 45 hook over the edges of suitable openings in the supporting plate 18. The connection between the connecting bracket 15 and the supporting plate 18 is effected by two movements, first, a movement of insertion to 50 bring the hook members 19 back of the plate 18, and second, a downward movement to engage the hook members with the edges of the opening.

The sliding connection between the plug- 55 in device 14, and the connecting bracket 15,

hereinbefore referred to, permits the downward movement of the connecting bracket 15 without interference from the engagement of the blades 16 in the openings 17. This sliding connection of the plug-in device 14 with the connecting bracket 15 is effected by a pair of lugs 20 struck up from the material of the bracket 15, the insulating base 21 of the plug-in device lying between the lugs 20 on one side, and the body portion of 60 the bracket 15 on the other side. The plug-in device 14 is prevented from lateral movement with respect to the connecting bracket 15 by means of cheek-pieces 22 formed integral with the bracket, the insulating base 70 21 lying between these cheek-pieces. The lugs 20 may be bent down after the insulating base 21 is placed in position on the bracket. The bracket 15 may be a sheet metal stamping, the lugs 20, the cheek- 75 pieces 22, and the hooks 19 being formed as integral parts of this stamping.

In order to hold the bracket 15 in connected position on the plate 18, latch means are provided for preventing movement of 80 the bracket 15 upwardly.

These means comprise a slidably mounted finger 23, which extends through an opening 24 in the bracket 15, and can be made to engage underneath the insulating base 21 85 of the plug-in device shown in Fig. 1. When thus engaged, it will be seen that the bracket 15 cannot be moved upwardly and hence the hook members 19 cannot be disconnected from the supporting plate 18. 90

The outer end of the finger 23 has a loop or eye portion 25, which surrounds the fixture stem 11 and is slidable thereon, a coil compression spring 26 being provided tending to hold the latching finger 23 in latching 95 position.

In order to release the latching finger 23 when desired, an operating sleeve 27 is provided on the end of which the coil compression spring 26 bears, and the outer end of 100 which is provided with an outwardly extended beaded portion 28, lying outside the canopy 12. The outer end of the coil compression spring 26 bears on a washer 29 secured to the stem 11, which washer serves as 105 an abutment for supporting the outer end of the spring. As the beaded portion 28 of the operating sleeve 27 is accessible from the outside of the canopy, all that is necessary in order to effect the release of the latching 110

finger 23 is to pull outwardly on the beaded portion 28.

After the latching finger 23 has been pulled out from underneath the insulating base 21, the bracket 15 can be unhooked from the supporting plate 18 simply by lifting up on the fixture stem 11 until the hooks 19 are free from the supporting plate 18, when the entire device can be pulled away from the supporting plate.

It will be noted that the beaded portion 28 of the slidable sleeve 27 not only serves as a handle portion for operating the latching finger 23, but also bears on the canopy 12 to hold its inner edge against the supporting surface 30.

The fixture 10 may be secured to the bracket 15 by means of a sheet metal strap 31, to which the fixture stem 11 is secured, which strap is secured to the bracket 15 by means of screws 32. This strap 31 may have laterally extending fingers 33, which serve to steady the canopy 12 when the device is disconnected from the receptacle, and prevents the canopy from slipping off from the stem 11. The usual ornamental finishing plate or escutcheon 34 may be provided in front of the supporting plate 18.

Having thus described my invention what I claim as new and desire to secure by Letters Patent of the United States is:

1. The combination with a fixture having a stem, and a receptacle, of means for electrically and mechanically connecting said fixture with respect to said receptacle comprising a supporting plate, a bracket connectible with said plate by movement toward said plate and laterally with respect thereto, a plug-in device mounted for bodily sliding movement with respect to said bracket, means for retaining said bracket in connected position, and means for releasing said retaining means comprising a sleeve surrounding said stem.

2. The combination with a fixture having a stem, and a receptacle, of means for electrically and mechanically connecting said fixture with respect to said receptacle comprising a supporting plate, a bracket connectible with said plate by movement toward said plate and laterally with respect thereto, a plug-in device mounted for bodily sliding movement with respect to said bracket, means for retaining said bracket in connected position, and means for releasing said retaining means comprising a sleeve surrounding said stem, and slidable thereon.

3. The combination with a fixture having a stem, and a receptacle, of means for electrically and mechanically connecting said fixture with respect to said receptacle, comprising a supporting plate, a bracket connectible with said plate by movement toward said plate and laterally with respect thereto, a plug-in device mounted for bodily

sliding movement with respect to said bracket, and means for retaining said bracket in connected position comprising a latch member and a coil spring surrounding said stem for holding said latch member in latching position.

4. The combination with a fixture and a receptacle, of means for electrically and mechanically connecting said fixture with respect to said receptacle comprising a supporting plate, a bracket connectible with said plate by movement toward said plate and laterally with respect thereto, a plug-in device mounted for bodily sliding movement with respect to said bracket, said bracket having an opening therein, and means for retaining said bracket in connected position comprising a finger slidable through the opening in said bracket.

5. The combination with a fixture and a receptacle, of means for electrically and mechanically connecting said fixture with respect to said receptacle comprising a supporting plate, a bracket connectible with said plate by movement toward said plate and laterally with respect thereto, a plug-in device mounted for bodily sliding movement with respect to said bracket, said bracket having an opening therein, and means for retaining said bracket in connected position comprising a finger slidable through the opening in said bracket, and engageable with said plug-in device to prevent relative movement between said plug-in device and bracket.

6. The combination with a fixture having a stem, a canopy having an opening through which stem extends, and a receptacle, of means for electrically and mechanically connecting a fixture with respect to said receptacle, means for retaining said fixture mechanically connected, and means for releasing said retaining means comprising a sleeve surrounding said stem and extending through the opening in said canopy.

7. The combination with a fixture having a stem, a canopy having an opening through which said stem extends, and a receptacle, of means for electrically and mechanically connecting said fixture with respect to said receptacle, and spring actuated means for retaining said fixture mechanically connected and for pressing said canopy against a supporting surface.

8. The combination with a fixture having a stem, a canopy having an opening through which said stem extends, and a receptacle, of means for electrically and mechanically connecting said fixture with respect to said receptacle, and spring actuated means for retaining said fixture mechanically connected and for pressing said canopy against a supporting surface, said last means comprising a sleeve surrounding the stem and extending through the opening in the canopy.

and bearing on the canopy to hold it against a supporting surface.

9. The combination with a fixture having a stem, a canopy having an opening through which said stem extends, and a receptacle, of means for electrically and mechanically connecting said fixture with respect to said receptacle, means for retaining said fixture mechanically connected comprising a latch member and a spring surrounding said stem and bearing on said latch member, and means for releasing said retaining means and holding said canopy in position comprising a sleeve surrounding said stem and spring and extending through the opening in said canopy, and bearing on said canopy to hold the edge of the canopy against a supporting surface.

10. The combination with a fixture having a stem, a canopy having an opening through which said stem extends, and a receptacle, of means for electrically and mechanically connecting said fixture with respect to said receptacle, comprising a bracket, and wings mounted on said bracket and engaging said canopy for steadyng said canopy in position.

11. The combination with a fixture having a stem, a canopy having an opening therein through which said stem extends, and a receptacle, of means for electrically and mechanically connecting said fixture with respect to said receptacle, means for retaining said fixture mechanically connected, and means for releasing said retaining means comprising a sleeve slidable on said stem and extending through the opening in said canopy.

12. The combination with a fixture having a stem, a canopy having an opening therein through which said stem extends, and a receptacle, of means for electrically and mechanically connecting said fixture with respect to said receptacle, means for retaining said fixture mechanically connected, comprising a spring surrounding said stem, and means for releasing said retaining means comprising a sleeve slidable on said stem and

surrounding said spring, and extending through the opening in said canopy.

13. A fixture having a stem, a receptacle, a supporting plate in front of said receptacle having an aperture affording access to said receptacle, said receptacle being substantially flush with said supporting plate, means for supporting said fixture in position with respect to said receptacle comprising a bracket having hooks for passing through said supporting plate and hooking in behind it, means for electrically connecting said fixture with respect to said receptacle comprising a plug having contacts for engaging the receptacle contacts, said plug-in device being slidably mounted on said bracket, whereby said hooks can be hooked in behind said supporting plate after the plug-in contacts have entered the receptacle, means tending to prevent upward movement of the bracket to disconnect the hooks, and means for releasing said preventing means comprising a sleeve surrounding the fixture stem.

14. A fixture having a stem, a receptacle, a supporting plate in front of said receptacle having an aperture affording access to said receptacle, said receptacle being substantially flush with said supporting plate, means for supporting said fixture in position with respect to said receptacle comprising a bracket having hooks for passing through said supporting plate and hooking in behind it, means for electrically connecting said fixture with respect to said receptacle comprising a plug having contacts for engaging the receptacle contacts, said plug-in device being slidably mounted on said bracket, whereby said hooks can be hooked in behind said supporting plate after the plug-in contacts have entered the receptacle, means tending to prevent upward movement of the bracket to disconnect the hooks comprising a spring-pressed finger slidably mounted to move perpendicularly to said supporting plate.

In witness whereof, I have hereunto subscribed my name.

REUBEN B. BENJAMIN.
